TUFTING MACHINE

Murl A. White, Sumter, S. C., assignor to Polly Prentiss, Inc., Sumter, S. C., a corporation of South Carolina

Application June 14, 1937, Serial No. 148,228

7 Claims. (Cl. 112—79)

My invention relates to tufting machines.

An important object of the invention is to provide a machine of the above mentioned character, which is extremely simple in construction, 5 compact, and reliable in operation.

A further object of the invention is to provide means whereby the looper and cutter may be readily removed as a unit.

A further object of the invention is to provide 10 means whereby the looper is moved by the cutter.

A further object of the invention is to provide means to operate the cutter, which means is independent of the work feed means.

15 Other objects and advantages of the invention will be apparent during the course of the following description.

In the accompanying drawings forming a part 20 of this application and in which like numerals are employed to designate like parts throughout the same,

Figure 1 is a side elevation of a tufting machine embodying my invention, parts in section, and parts broken away,

25 Figure 2 is a front end elevation of the same, parts in section.

Figure 3 is a side elevation of the cutter and looper and associated elements, parts in section and parts omitted, with the needle raised,

30 Figure 3a is a similar view with the needle lowered,

Figure 4 is a perspective view of the operating parts of the machine,

Figure 5 is a vertical view taken on line 5—5 35 of Figure 2,

Figure 6 is an exploded perspective view of the cutter, looper, and associated elements,

Figure 7 is a diagrammatic view showing the 40 relative movements of the looper and blade, and,

45 Figure 8 is a vertical section through the stock showing the rock-shafts journaled therein.

In the drawings wherein for the purpose of illustration is shown a preferred embodiment of my invention, the numeral 10 designates a sewing machine as a whole, of any well known or preferred type, such as the ordinary Singer sewing machine, comprising a stock 11, arm 12 and head 13. The stock is mounted upon a flat base 14. The head 13 is provided with the usual vertical reciprocating needle bar 15 having a needle 16 clamped thereto. This needle has the usual eye at its lower pointed end for receiving the tufting yarn or thread, passed through the usual guide and tension means, not shown.

50 The machine comprises the usual drive shaft

17, suitably journaled in the arm 12, and horizontally arranged, as shown, and driven by a grooved pulley 18, which may be manually or power driven. At its forward end the drive shaft 17 is provided with a crank disc 19 rigidly secured thereto, and having pivotal connection with a link 20. This link is pivotally connected with a sleeve 21, which is clamped to the needle bar 15. The machine further comprises a presser foot 22, of the usual construction, clamped to a presser bar 23, moved downwardly by the usual spring and raised by a finger engaging lever 24.

5 The arranged below the base 14 are horizontal rock shafts 25 and 26, which are held in suitable 5 bearings. The sewing machine further comprises work feed means, to advance the work from the operator, including work feed dogs 27, operating through a suitable opening in the base or through the throat plate, as is well known. These dogs are actuated by a rigid dog supporting bar or link 28, to which they are rigidly secured. At one end, the bar or link is rigidly connected with a transverse head 29, which is pivotally connected with upstanding cranks 30, in turn rigidly mounted upon the rock shaft 25. At its opposite end the rigid bar or link 28 is provided with a fork 31, receiving a roller 32, pivotally mounted upon a crank 33, in turn rigidly mounted upon the rock shaft 26. The rock shafts therefore serve as the operating means for the 10 bar 28, serving to actuate the work feed means. These rock shafts extend longitudinally of the drive shaft 17 and are parallel therewith. The rock shafts 25 and 26 are provided adjacent to the stock 11 with cranks 34 and 35 respectively. The cranks 34 and 35 are pivotally connected with connecting rods 36 and 37 respectively, which are actuated by cams 38 and 39 respectively, in turn carried and driven by the drive shaft 17. It might be stated at this point that the rock shaft 25 serves to move the dog carrying bar or link 28 longitudinally, while the rock shaft 26 serves to raise and lower the same. The rock shaft 17 is also provided with a crank 40. The foregoing description is that of the ordinary Singer sewing machine.

45 Depending from the base 14 are lugs 41 and 42, within which is mounted an auxiliary rock shaft 43, arranged between the rock shafts 25 and 26, and parallel therewith. Rigidly connected with the rear end of the rock shaft 43 is a crank 44, having a block 45 pivotally connected therewith, and sliding in an elongated slot 46 of a bell crank lever 47. This bell crank lever is carried by a rock shaft 48, journaled in stationary bearings 50

55

formed in the base 14. Pivots connected with the end of the bell crank lever 47, at 48, is a connecting rod 50, extending upwardly, for pivotal connection with the crank 48. It is thus seen that the rock shaft 43 is rocked by the continuous rotation of the drive shaft 17. At its forward end, the rock shaft 43 is provided with a disc or wheel 58, carrying a crank pin 51, eccentric therewith. This crank pin operates beneath the dog bar 28 but does not contact therewith.

A support is provided for the cutter and looper, to be described, and this support is removable with the cutter and looper as a unit from the lug 15 41, to which it is attached. This support comprises a plate 52, Figure 6, having a horizontal flange 53, carrying a rib 54, which is separate from the lug 41. The plate 52 has elongated vertical slots 55, to receive set screws 56. While the plate 52 is shown as adjustable, for the purpose of raising and lowering the looper, yet the adjustability may be dispensed with and plates of different height used. Coacting with the plate 52 is a plate 57, having a horizontal flange 58, provided with elongated slots 59, receiving set screws 60, to engage within screw threaded openings 61. The plate 57 is adjustable longitudinally of the plate 52, but this adjustability is not essential, as plates of different lengths may be used.

The numeral 62 designates a looper as a whole, comprising an arm 63, provided at its upper end with a looper element 64, having a down turned end or hook 65. It is preferred to use the down turned end 65 but this may be omitted under certain conditions. The arm 63 has a recess 66 and the arm is provided at its lower end with a vertical elongated slot 67, to receive a pin or stud 68, rigidly attached to the plate 57. This stud serves as a fixed pivot upon which the lower end of the looper 62 turns. The looper slidably engages the flat face of the plate 57, and the looper is mounted to swing vertically in the direction of the feed of the work, and the looper element 64 has its free end facing in an opposite direction to the feeding movement of the work, and this looper element is adapted to move across the path of travel of the needle 16, when the needle is lowered, to receive the loop from the needle, and to hold the loop from pulling out of the fabric when the needle rises. The plate 57 carries a fixed pivot element 69, which is free from connection with the looper 62 and does not support the looper, but operates within the recess or cut out portion 66 without contacting with the looper. The numeral 70 designates a blade or cutter, having an angularly disposed cutting edge 71 near its top for shearing action with the looper element 64 preferably having a cutting edge 72. The cutting edge 71 rubs against the cutting edge 72. The blade or cutter 70 slidably contacts with the looper 62 and this blade or cutter is provided with an opening 73, pivotally receiving the pin or pivot 68. This pivot element constitutes the sole support of the blade or cutter 70. The looper 72 does not carry the blade or cutter 70 but the looper is carried in a floating manner by the reciprocating blade or cutter 72 and for this purpose the blade or cutter 70 is provided near its upper end with a pin or stud 74, rigidly attached to the blade 70 and this pin or stud is pivotally mounted within an opening 75, formed in the upper portion of the looper. It is thus seen that the blade or cutter 70 turns upon the pivot 68, while the looper 72 turns upon the pin or stud

68. Since the upper end of the blade or cutter 70 is nearer to the pin 68 than the upper end of the looper 62 is to the pin 68, and since the upper ends of the blade and looper are connected to move together, their upper ends move horizontally for the same distance, but due to the difference in the length of the radius of the swinging parts, the blade or cutter 70 will be inclined or angularly displaced to a greater extent than the looper, whereby a relative angular movement is effected between the blade and looper, causing the cutting edge 71 of the blade to sever the loops upon the looper element 64. Means are provided to reciprocate the blade or cutter 70, comprising an arm or crank 76, having a head 77. The head is provided with an opening 78 to pivotally receive the pin 68 and the head also has an opening 79 which is elongated and receives a set screw 80, engaging within a screw-threaded opening 81 formed in the blade 20 or cutter 70. The arm 76 has an elongated slot 82, to receive the crank pin 61. The arm or crank 76 may be angularly adjusted with respect to the blade or cutter 70, to regulate the length of the stroke of the blade. The pivot element or pin 68 extends through the opening 78, as stated, and through a washer 83, having a cut out portion 84 to receive the head of the set screw 80. A nut 85 has screw-threaded engagement with the outer end of the pin 68 and 30 is held against turning movement by a lock nut 86, and a spring 87 is arranged between the nut 85 and the washer 83.

In view of the foregoing description it is thus seen that the looper 62 and the blade 70 and 35 associated elements are all bodily mounted upon the support including the plate 52, and by removing the plate 52 from the lug 41, the support, looper and blade may be removed as a unit.

The operation of the machine is as follows: 40

When the needle 16 is near its uppermost position, the crank pin 61 is raised and swings the arm or crank 76 counter-clockwise, as viewed from the front in Figure 3. The crank therefore swings the blade or cutter 70 counter-clockwise and the blade in turn swings the looper counter-clockwise, causing the looper to travel from the needle. Since the pivots of the blade and looper are eccentric, their upper ends swing in circularly curved eccentric paths, and since 50 the extent of horizontal movement is the same, the extent of angular displacement or movement of the blade 70 is greater than that of the looper, effecting a relative turning movement between the blade and looper and causing the blade to sever the loop or loops upon the looper 64, but leaving the last loop unsevered. The extent of throw of the blade may be regulated by adjusting the crank 76 so that the last loop will not be cut. While it is preferred to move the 60 blade so that it will not cut the last loop, the invention is not necessarily restricted to this operation. As the needle descends the crank pin 61 is traveling downwardly, and swings the arm or crank 76 clock-wise, looking from the front in Figure 3a, and the crank 76 then swings blade 70 clock-wise, which in turn swings looper 62 clock-wise, causing the looper to travel toward the needle. The looper continues to move toward the needle and moves across the path of travel of the needle by about the time the needle has reached or slightly passed its lowermost position and continues to move slightly toward the needle as the needle begins to ascend. The looper therefore receives the loop thereon as the 70 75

needle rises, and as the needle approaches or reaches its uppermost position, the looper moves from the needle. The cutting edge 71 of the blade 70 moves toward the looper element 64 as 5 the blade and looper element move from the needle, to sever the loop or loops upon the looper, and the cutting edge 71 moves from the looper element as the looper element moves toward the needle to provide a suitable space for the loop 10 when the looper element enters the loop.

It is to be understood that the form of my invention herewith shown and described is to be taken as a preferred example of the same and that various changes in the shape, size, and 15 arrangement of parts, may be resorted to without departing from the spirit of my invention or the scope of the subjoined claims.

Having thus described my invention, what I claim is:

20 1. In a tufting machine, a reciprocatory needle to carry the yarn through the fabric and produce a loop, work feed means for coaction with the needle, a swinging looper arranged to engage the loop produced by the needle and having an 25 opening near its upper end and an elongated opening near its lower end, a pivot element engaging within the elongated opening, a second pivot element separate from the first named pivot element and the looper, a blade having an opening 30 to receive the second pivot element, a part carried by the blade to engage within the upper opening of the looper, the blade having a shearing action with the looper, an arm carried by the blade and having an elongated opening, a rock 35 shaft, a crank pin carried by the rock shaft and extending into the elongated opening, means to drive the rock shaft, and yielding means to move the blade toward the looper.

2. In a tufting machine, a reciprocatory needle 40 to carry the yarn through the fabric and produce a loop, work feed means for coaction with the needle, a pivot element, a swinging looper arranged to engage the loop produced by the needle and engaging near its lower end with the pivot 45 element to turn about the same, a second pivot element separate from the first named pivot element and separately mounted from the looper and arranged between the first named pivot element and the upper end of the looper, a blade 50 pivotally mounted upon the second named pivot element to sever the loops upon the looper, means connecting the upper portions of the blade and looper so that the looper is moved by the movement of the blade, an arm connected with the 55 blade to swing the same upon its pivot and disposed between the first named pivot element and the upper end of the looper, an element to engage the arm to reciprocate the same, and means to move the element.

60 3. In a tufting machine, a reciprocatory needle to carry the yarn through the fabric and produce a loop, work feed means for coaction with the needle, a reciprocatory looper for coaction with the needle to enter the loop, means forming a 65 mounting for the reciprocatory looper, a blade

to sever the loops upon the looper, a pivot element forming a mounting for the blade and separate from the looper and arranged between the upper and lower ends of the looper, said blade having a part provided with an opening, said part being 5 arranged between the upper and lower ends of the looper, a turning element operating within said opening to move the blade, means to move the turning element, and means connecting the upper ends of the looper and blade so that the 10 looper is moved by the blade.

4. In a tufting machine, a reciprocatory needle to carry the yarn through the fabric and produce a loop, work feed means for coaction with the needle, a reciprocatory looper for coaction with the needle, means forming a mounting for the reciprocatory looper, a blade to sever the loops upon the looper, a pivot element forming a mounting for the blade and separate from the looper, a laterally extending arm carried by the 20 blade, said arm being arranged between the upper and lower ends of the looper, and a rocking element engaging the arm to reciprocate the same, and means connecting the upper ends of the looper and blade. 25

5. In a tufting machine, a reciprocatory needle to carry the yarn through the fabric and produce a loop, work feed means for coaction with the needle, a reciprocatory looper for coaction with the needle, a blade to sever the loops upon the 30 looper, a pivot element for supporting the blade and separate from the looper, an arm, adjustable means to clamp the arm to the blade in a selected angular position with relation thereto, means to reciprocate the arm, and means operated by the blade to move the looper. 35

6. In a tufting machine, a reciprocatory needle, work feed means for coaction with the needle, a vertically swinging looper for coaction with the needle, a vertically swinging blade to sever the 40 loops upon the looper, a pivot element for supporting the blade and separate from the looper and arranged between the upper and lower ends of the looper, an element carried by the blade to swing the same about its pivot and arranged between the upper and lower ends of the looper, means to reciprocate the element, and an element moved by the blade and serving to move the looper. 45

7. In a tufting machine, a reciprocatory needle, work feeding means for coaction with the needle, a vertically swinging looper provided between its upper and lower ends with a recess, a pivot element engaging the lower end of the looper, a blade to sever the loops upon the looper, a pivot 50 element for the blade and separate from the looper and adapted to be received within the recess of the looper, a pivot element connecting the upper ends of the blade and looper so that the looper is driven by the blade, an arm carried by the blade and arranged near the pivot element of the blade and having an opening, and a turning operating element engaging within the opening. 55

MURL A. WHITE. 60
